OF ATLANTA, GEORGIA, A CORPORATION OF GEORGIA

KNITTING NEEDLE

Application filed June 2, 1931. Serial No. 541,643.

This invention relates to knitting needles for knitting machines, and more particularly to a needle adapted to be used in knitting a padding backed with woven burlap or the like.

One of the principal objects of the invention is to provide a needle having an inner needle reciprocally mounted within the outer needle, the hook of the inner needle being located within a slotted portion of the hook of the main or outer needle, whereby, when the inner needle is in one extremity of its movement, its hook will be in position to receive the thread for the formation of a stitch, and when at the opposite extremity of its movement, will transfer the thread partially to the hook of the outer needle, and whereby the hook of the inner needle will be held against lateral displacement by reason of the slotted or recessed hook of the outer needle, within which it reciprocates.

A further object of the invention is to provide a needle of this type in which the inner needle has a swelled portion projecting out from the slot of the outer needle below the point of the latter, for engagement with the cloth backing, whereby reciprocation of the inner needle with reference to the outer needle is automatically obtained, and whereby the outer hook is closed during the movement of the outer needle in one direction, and is opened during the movement of the needle in the opposite direction.

A further object of the invention is to provide a needle of this type, in which the entire inner needle, including its hook, with the exception of the bulged portion of the inner needle, is wholly encased within the outer needle.

Another object is to provide a needle such as described, in which the inner needle has its upper end pointed to form, by contact with the inner surface of the hook of the outer needle, a stop of small area, to thereby prevent a binding engagement between the inner and outer needles at the upper limit of movement of the former, and to thus prevent any tendency of the inner needle being held against ready movement in an opposite direction.

Another object of the invention is to provide the inner needle with a guide means in the form of a reduced shank, which cooperates with a pin extending through the outer needle and with the walls of the slot in the outer needle, and to also provide the inner needle with a curved seat at the junction of the shank and the body portion of the inner needle, to form in conjunction with the pin, a stop for limiting the lowering movement of the inner needle, and without a binding effect. 55

A still further object is to provide the inner needle with a throat which substantially corresponds in width with that of the outer needle, when the former is in thread-receiving position, to thereby form no obstruction or hindrance to the looping of the thread in the needle, and to incline the throats of the inner and outer needles at an angle to the line of movement of the inner needle, so that when the latter is moved to position for closing the throat of the outer needle, the bottom or thread-engaging wall of the inner needle will be displaced somewhat inwardly of the corresponding wall of the throat of the outer needle, to thereby distribute the support of the thread loop over the hook of the inner needle as well as the side walls of the outer needle. 60 70 75

With these and other objects in view, which will become more apparent as the description proceeds, reference is made to the accompanying drawing, which discloses one of the variety of forms that the invention may take, and in which,— 80 85

Figure 1 represents an end elevational view of a needle segment removed from a knitting machine, showing a needle in side elevation.

Figure 2 represents an enlarged longitudinal sectional view through the needle. 90

Figures 3 and 4 represent elevational views, partially in section, showing different positions in the operation of a needle in knitting a padding onto a woven burlap backing. 95

Figure 5 represents a horizontal sectional view taken on the line 5—5 of Figure 3, on an enlarged scale.

Referring more particularly to the drawing, the main or outer needle 5 is provided with a slot 6, which extends around the hook 100

7 of the needle as at 8, and in which slot the inner needle 9 is located.

The latter is provided with a hook 10 which is located within the hook 7 of the outer needle, the point 11 of the inner hook being located within the slot which extends down the hook of the outer needle to near the point thereof. The point of the inner hook is thus housed in such slot against engagement 5 with the thread as the latter is looped upon the needle and moves up into the throat thereof, the outer wall 12 of the throat 13 of the inner hook forming substantially a continuation of the lower outer wall 14 of the throat 15 of the outer hook. This arrangement appears from Figure 2, in which the parts are shown in the position assumed when the inner needle is at the lower end of its path of travel, the throat of the outer needle 10 being open, and the needle as a whole, being in condition to have the thread loop passed about its hook. Figures 3 and 1 also illustrate this condition of the needle, the thread loop as it is formed about the needle, ready 15 to be engaged in the hook of the needle as the latter descends, being indicated in Figure 3 at A.

The throat 13 of the inner hook is substantially of the same width as the throat 15 of the outer hook, the lower or thread-engaging wall 16 of the inner hook registering with the corresponding wall 17 of the outer hook when the inner needle is in its lower position. The walls 14 and 17 of the throat of the outer 20 needle are arranged at an angle to the longitudinal axis of the needle, which axis coincides with the path of movement of the inner needle, and hence after the loop has been engaged in the needle, and the inner needle 25 moves upwardly, its lower wall 16 shifts slightly inwardly with reference to the walls 17 of the throat of the outer needle, whereby the loop of the thread A, will be supported by the wall of the throat of the inner needle, 30 as well as by the walls of the throat of the outer needle, as indicated in Figure 5. This forms a smooth bend in the thread, without abrupt turns, and hence not only relieves the thread from danger of weakening abrasion, 35 but distributes the wear on the needle as a whole between the inner and outer needles.

The inner needle is formed with a bulged portion 18, which projects beyond the edge of the outer needle below the hook of the latter, to provide shoulders at 19 and 20, the purpose of which will more fully hereinafter appear. These shoulders are preferably curved as illustrated, the edge of the upper shoulder merging with the lower wall of the 40 throat of the inner needle, so as to smoothly guide the loop of the thread into the hooked portion of the needle. When the inner needle is in its upper position with reference to the outer needle, as illustrated in Figures 3 and 45 4, the shoulder 19 of the inner needle having

traversed the width of the throat of the outer needle, engages the point of the outer hook, to close the throat and condition the needle to shed the loop, illustrated at B, which has previously been formed on the needle, and to 50 also prevent the point of the hook from catching in the woven backing as the needle descends. If desired, the shoulder 19 may be provided with a counter-sunk depression as at 21, to receive the tip of the hook of the outer needle, to insure against the thread 55 catching in the latter as the loop B is shed.

The upper end or hooked portion of the inner needle may be somewhat pointed as at 22, such point being adapted to engage the bottom wall of the slot 8 in the outer needle hook, to limit the upward movement of the inner needle when the throat of the outer needle has been closed, to thus provide a stop of small area which will prevent any binding 60 action between the inner and outer needles taking place, and which might otherwise retard the ready downward movement of the inner needle when the time for such movement arrives. If desired, the depression 21 in the upper shoulder of the inner needle 65 may be made sufficiently large to accommodate the point of the hook of the outer needle, and to allow such point to abut against the bottom wall of the depression in order to 70 form a stop for the upward movement of the inner needle. In either event a stop of relatively small area is provided, which prevents any binding action taking place between the inner and outer needles when the latter is at 75 the upper limit of its movement.

The inner needle is provided with a downwardly extending reduced shank 23 which slidably fits within the walls of the slot of the outer needle, and between the base of the slot and the pin 24 which pierces the side walls of the slot. Such shank sliding between the pin and the walls of the slot, maintains the inner needle in proper alignment during its reciprocal movements within the outer needle. At the junction of the shank 23 with the body portion of the inner needle there-above, a seat 25 is provided which preferably curves over the upper face of the pin 24, to form a stop for the lowering movement of the inner needle. Such seat being curved over the upper wall of the pin, properly centers the inner needle and prevents any binding or wedging action taking place between the inner needle and the base 100 of the slot as the former approaches its lowermost position.

Referring more particularly to Figures 3 and 4, the woven backing is indicated at C, and a sliver of the padding is indicated at 105 D. In Figure 3 the right hand needle has moved upwardly, the point 26 having pierced the backing, and a new loop of the thread A has been formed about the needle. As the latter moves downwardly in its reciprocal 110

motion, the loop of the thread A moves up into the throat of the needle, and as the shoulder 20 of the bulged portion 18 of the inner needle engages the backing C, the resistance afforded by the backing to the passage of the bulged portion of the inner needle, forces the latter upwardly, to close the throat of the outer needle, and to place the needle as a whole in a condition to shed the loop B, occurring below the backing, and which has already been formed on the needle. This upward movement of the inner needle will be assisted by the pull exerted on the hook of the inner needle by the loop of the thread A, as the needle moves downwardly.

Continuing its downward movement, the needle emerges from below the backing, with its throat in closed condition, the loop B slips upwardly over the bulged portion of the inner needle and over the hook of the outer needle, is shed, and slips onto the thread A, the loop of the latter remaining within the hook of the needle. As the needle again rises, in continuing the knitting operation, it pierces the backing, and the upper shoulder 19 of the bulge of the inner needle engaging upon the under side of the backing as the needle passes therethrough, forces the inner needle downwardly, allowing the loop of the thread A to slip downwardly over the shoulder 19 and the bulge of the inner needle and onto the body of the needle to occupy the position formerly occupied by the loop B, as shown in Figure 3. Thus the needle moves upwardly through the backing after the bulged portion has passed therethrough, with its throat open ready to receive a new loop. The doffing bars or guide plates for the material are indicated at E.

From the foregoing, it is believed that the operation of the needle will be clearly understood by those skilled in the art, without further explanation. While I have described the needle in connection with its usefulness in the knitting of a padding onto a woven backing, it will be understood that I do not intend my invention to be so limited in its use, as it may be used in many other knitting operations. The description has been given merely for the purpose of illustrating one of the uses to which the invention may be put.

It will be noted that the inner needle, except for the bulged portion 18 thereof, is wholly enclosed within the outer needle, and there are therefore no lateral projections or extensions of any kind that might tend to abrade the backing or fabric, if the needle is used in a knitting operation such as described, or to unnecessarily enlarge the opening made therein for the passage of the needle. Further, the hook of the inner needle being disposed in the slot provided in the hook of the outer needle, both at the front and rear thereof, is accurately guided and held against any lateral twisting or straining movements or

accidental displacement. Further, the construction is such that the single pin 24 serves to adequately retain the inner needle in position, and in co-operation with the reduced shank 23 guide the inner needle in its movements. This adds to the simplicity of the device and economy of manufacture. It will also be noted that the inner needle may be cheaply manufactured by mass production methods, by being stamped out of strip metal. The outer needle may also be economically stamped out of strip metal, and folded upon itself to form the channel for receiving the inner needle, and then turned over at its upper end and swaged or otherwise treated to form the point 26 of the needle and the pointed end of its hook, or it may be made out of solid stock and have its channel or slot formed therein. In either event, it is economical of manufacture.

While I have thus described one of the forms that the invention may take, and one of the uses to which it may be put, the foregoing description has been given for purposes of illustration and understanding of the invention only, and no limitations are to be deduced therefrom, but the claims should be construed as broadly as permissible, in view of the prior art.

Having thus described my invention what I claim as new, and desire to secure by U. S. Letters Patent is:—

1. In a knitting needle, the combination of an outer needle having a hook portion, said outer needle being provided with a slot extending around the inner side of the hook portion to adjacent the point thereof, and an inner needle slidably mounted in the slot of the outer needle and having a hook located within the hook portion of the outer needle, the edges of the hook of the inner needle extending into the slot of the outer needle at the front and back of the hook portion thereof.

2. In a knitting needle, the combination of an outer needle having a hook portion and being provided with a slot extending around the inner sides of the hook, and an inner needle slidably mounted in the slot of the outer needle and provided with a hook, the edges of which are located in the slotted hook of the outer needle.

3. In a knitting needle, the combination of an outer needle having a hook portion and being provided with a slot extending around the inner walls of the hook, and an inner needle slidably mounted in the slot and provided with a hook, the edges of which extend into the slotted hook of the outer needle, the edges of the throat of the outer needle hook being inclined to the direction of travel of the inner needle, and the thread-engaging wall of the inner needle hook being similarly inclined.

4. In a knitting needle, the combination of

an outer needle having a hook portion, and being provided with a slot which extends around the inner sides of the hook portion, and an inner needle slidably mounted in the slot of the outer needle and having a hook portion located within the hook of the outer needle and extending at its edges into the slot thereof, said inner needle being provided with a bulged portion extending beyond one edge 10 of the outer needle, the inner needle except at its bulged portion, being wholly mounted in the slotted portions of the outer needle.

5. In a knitting needle, the combination of an outer needle having a hook portion and 15 being provided with a slot which extends around the inner sides of the hook portion, and an inner needle slidably mounted in the slot of the outer needle and including a hook portion encased within the hook of the outer 20 needle, said inner needle having a bulged portion extending beyond one edge of the outer needle.

6. In a knitting needle, the combination of an outer needle having a hook portion, and 25 being provided with a slot extending around the hook portion thereof, an inner needle mounted for reciprocation in the slot and including a hook portion encased within the slot of the hook portion of the outer needle, said 30 inner needle being provided with a bulge extending beyond one edge of the outer needle and being provided with a reduced shank enclosed between the walls of the slot, and a pin carried by the outer needle and between 35 which and the walls of the slot, said shank is guided, there being a seat arranged at the junction of the said reduced shank and the bulge of the inner needle and adapted to engage said pin for limiting the movement of 40 the inner needle in one direction.

7. In a knitting needle, the combination of an outer needle having a hook portion and being provided with a slot extending around the inner walls of the hook portion, 45 an inner needle slidably mounted within the slot of the outer needle and including a hook portion extending at its edges into the slot in the hook portion of the outer needle, the hook portion of the inner needle being provided with a tapering point adapted to engage a wall of the slot of the outer needle to limit the movement of the inner needle in one direction.

In testimony whereof I hereunto affix my
55 signature.

MARTIN LUTHER PLEDGER.
